Primary Examiner — Clare E Heflin(74) Attorney, Agent, or Firm — Meschkow & Gresham, P.L.C.(57) CLAIM

The ornamental design for a surface mounted light fixture, as shown and described.

DESCRIPTION

FIG. 1 is a top perspective view of a surface mounted light fixture, showing my new design therefor;

FIG. 2 is a bottom perspective view of a surface mounted light fixture therefor;

FIG. 3 is a top view thereof;

FIG. 4 is a bottom view thereof; and,

FIG. 5 is a side view thereof, showing one side, the three other sides being the same image thereof.

The broken lines shown on the drawings depict portions of the light fixture that form no part of the claimed design.
